9 Inventor,
Victor Adams
By Jno. L. Elliott, Attorney.

UNITED STATES PATENT OFFICE.

VICTOR ADAMS, OF CHICAGO, ILLINOIS.

HEAD FOR BROOMS AND BRUSHES.

Application filed August 19, 1916. Serial No. 115,767.

To all whom it may concern:

Be it known that I, VICTOR ADAMS, a citizen of the United States, and resident of Chicago, in the county of Cook and State 5 of Illinois, have invented certain new and useful Improvements in Heads for Brooms and Brushes, of which the following is a full, clear, and exact specification.

This invention relates to improvements 10 in heads for brooms and brushes, in which heretofore bunches of bristles have been secured to a head of wood by means of staples, or else clamped and tightened in a sheet metal head by means of rivets secured to 15 the head and passing through the bristles.

The prime object of my invention broadly stated is to provide a simple and durable means particularly adapted for conveniently and quickly securing the bunches of 20 bristles in their operative position to a broom or brush head, and which when worn may be readily replaced by other bunches of bristles.

A further object of my invention is to 25 provide a broom or brush head of such a construction that any desired number of bunches of bristles may be quickly and conveniently attached thereto in their operative positions, and in as many rows staggered, or otherwise, as may be necessary for 30 the particular use to which they are to be applied.

Another object of my invention is to provide a means by which broom and brush 35 heads and the fastenings for their bunches of bristles may be in their entirety constructed from sheet metal, the several parts of which brush head may be rigidly and permanently locked together in their operative 40 position, with the fewest possible number of rivets consistent therewith, and likewise by clips, nuts or bolts for detachable purposes, if need be.

A further object of my invention is to 45 have such a head provided with a handle socket formed integral therewith, and in which the handle may be securely locked therein against detachment by means of a metallic clip.

With these ends in view, my invention 50 finds embodiment in certain features of novelty in the construction, combination and arrangement of parts by which the said objects and certain other objects are attained, 55 all as hereinafter fully described with reference to the accompanying drawings, and

more particularly pointed out in the claims.

In said drawings:

Fig. 1 illustrates a longitudinal vertical section on the line 1—1 of Fig. 2, a brush 60 head in which my invention finds its embodiment.

Fig. 2 is a horizontal section taken on the line 2—2 of Fig. 1.

Fig. 3 is a similar section taken on the 65 line 3—3 of Fig. 1.

Fig. 4 is a transverse section taken on the line 4—4 of Fig. 1.

Fig. 5 is a transverse section taken on the 70 line 5—5 of Fig. 1.

Fig. 6 is a perspective view of one of the binding clips for the several bunches of bristles.

Fig. 7 is a side elevation of a broom in 75 which my invention finds its embodiment.

Fig. 8 is a transverse section through the broom handle taken on the line 8—8 of Fig. 7.

Fig. 9 is a transverse section taken on the 80 line 9—9 of Fig. 10, and

Fig. 10 is a transverse section through the broom head taken on the line 10—10 of Fig. 7.

Similar characters of reference indicate 85 the same parts in the several figures of the drawings.

The application of my invention for the construction of brushes is illustrated in Figs. 1 to 6 inclusive in which the holder for two inner rows of bunched bristles for the 90 brush head consists of opposing strips of metal 12 and 13 extending transversely of the broom head respectively provided with right angle bends 14 and 15 at their opposite ends, providing overlapping ends for the 95 securing of said strips together, and to other parts of the broom head hereinafter referred to.

Surrounding the overlapped strips 12 and 100 13 are similarly formed strips 16 and 17, all of said strips being provided at intervals of their length with opposing slots 18—18 through which to project the legs 19 of a clip 20 adapted to separately bind each bunch of and secure the bristles to said strips following the projection of the legs 19 of the clips 105 through the parallel slots 18—18.

One edge of each leg 19 is inclined to a point as indicated at 21, in order that the legs may pass each other without increasing 110 the width of the clip when clamping a bunch of bristles in their operative position, and

whereby the tightening of the bristles in the clips and the flattening of the clips against their supporting strips 16 and 17 is facilitated and the resistance of the clips to the expansion of the bristles is correspondingly promoted.

The upper ends of the bends 14 and 15 of the inner strips 12 and 13 are bent inwardly beneath flanges 22 and 23 projecting inwardly from the upper edge of the strips 12 and 13 so that when strips are in their operative position these top flanges like the end flanges overlap each other.

Formed integrally with the strips 12 and 15 13 and projecting upwardly therefrom are overlapping socket pieces 24 and 25 in which to secure a handle 26 for the brush. This handle so formed is tightened and locked in its operative position by a clip or collar 27, one 20 end of which is provided with a slot 28, and the other end with a tongue 29 by bending its end over upon the collar as shown in Fig. 5.

It is now observed that the outer bristle supporting strips 16 and 17 are respectively 25 provided along their upper edges with hook shaped tongues 30 and 31 adapted to be passed through opposing slots 32 and 33 in the strips 12 and 13, and on their lower edges with tongues 34 and 35 bent upwardly over 30 the bottom edges of the inner strips 12 and 13, and whereby the strips 16 and 17 are not only bodily suspended from, but securely locked to the strips 12 and 13 against accidental detachment.

35 The brush head when constructed as now described, may be and preferably is provided with a cover 36 enclosing both its longitudinal sides and also its ends, and which may be of sheet metal bent to form, or other suitable material, and be secured to the brush head by means of bolts or rivets 37 passing therethrough and through the overlapping ends of the bristle supporting strips, as shown in Fig. 3.

40 In brushes, the bristles towards the outer ends thereof are preferably set at an angle slightly oblique to the length of the head, and for which purpose, as seen in Fig. 2, the slots in the strips for the clips for the bristles are accordingly set at an angle, and with the brush so constructed it will also be seen that means are provided for constructing a brush containing four rows of bristles, the bristles in the outer rows of which, excepting those at the extreme ends are in staggered relation with those of the inner rows, the inner rows being opposed to each other so that the clips by their contact provide a means for stiffening the brush head.

45 In Figs. 8 to 10 inclusive is illustrated the adaptation of my invention to a broom head in which the head 38 is necessarily substantially narrower and the bristles 39 of greater length than for a brush.

50 In the construction of a broom the head

therefor consists of outer strips 40 and 41 provided respectively at their opposite ends with right angle bends 42 and 43, the end edges of which are in meeting engagement, said strips being connected with opposing inner strips 44 and 45, the respective ends 46—46 and 47—47 are bent outwardly therefrom at a right angle and register with slots through which the ends are passed and then bent outwardly as indicated at 48—48 and 49—49, and then bent over upon the end portion of the strip as shown in Fig. 10.

The inner and outer strips are provided with slits in spaced pairs as in the brush, for the passage of clips 20 for the bristles, 80 of the form and construction before described, but are so arranged that the bristles of the outer strips 40 and 41 are located at the inner faces of said strips, while on the other hand for the strips 44 and 45 the bristles are located on the outer surfaces thereof and project between the bristles of their respectively opposing outer rows, the distance between the inner bristle holding strips being of a width corresponding with the thickness of two clips and the distance between the inner strips and the outer strips corresponding with the diameter of the clips, which therefore brace and strengthen the several strips and operate to render the 90 brush head a substantially rigid structure.

One of the inner bristle-suspending strips, as for example the strip 45 is provided at intervals along its upper edges with tongues 50 and at its bottom edge with tongues 51 100 (see Figs. 9 and 10) projecting across and bent over the edges and against the surface of the strip 46 as respectively indicated at 52 and 53.

The outer strips 40 and 41 are preferably 105 secured together at their meeting ends by means of clips 54, the legs of which are projected through suitable openings therefor in said strips and clinched, which clips as shown in Fig. 10 may also be utilized to secure in its operative position a curved guard strip 55 provided with an eye 56 through which the broom handle 57 is projected into a socket 58 sectionally formed integral with the strips 40 and 41 as before described in 110 connection with the brush shown in Fig. 1, and in which the broom handle is locked by means of a collar 59 of the construction shown in Fig. 1, the guard strip being provided with a felt cover 60 to prevent furniture being scratched when the broom is 115 in use.

The broom head 38 is also provided for the same purpose, with a surrounding felt strip 61 united in any convenient manner with 120 the guard strip 60.

The guard strip and its felt covering 61 is desirable for preventing the striking of the broom head and handle against furniture and adjacent walls when sweeping un- 130

der and behind furniture, but such a guard is not essential to my invention, though owing to its cheapness of construction and the convenience with which it may be rigidly held in its operative position, is accordingly desirable.

Among the advantages of my invention is its adaptability for the construction of heads both for brooms and brushes, in that it provides for the employment of metallic clips firmly and immovably securing bunches of bristles thereto, and which when of tin or galvanized metal are not deteriorated by moisture, oil, turpentine, or other volatile substances to which they are exposed, as heretofore, and that when locked in their operative position tightening the bristles against supporting metallic strips the construction of the clips provides a means for gripping of bristles so tightly that for practically an indefinite time they are prevented from detachment therefrom either singly or as a whole.

By the employment of sheet metal for the construction of the head of a brush or broom as herein shown and described, the cost of its construction is reduced to a minimum as will be understood from bearing in mind that the several strips and particularly the clips owing to the smallness of their dimensions may be constructed from sheet metal otherwise waste, and this whether of tin, sheet iron, or sheet steel, and that each and every separate piece and part may be constructed in its entirety with one stroke of a die, and a die which is comparatively cheap of production and requiring very little power for its successful operation.

It should here be observed that the clip construction herein shown and described is an important feature of my invention for securely binding and holding bunches of bristles for brushes, brooms and other articles, and that my invention is therefore not limited to the device herein shown and described for securing such bunches of bristles so clipped in their operative position in and to a broom head.

While I have described my invention as adapted for the use of bristles in brooms and brushes, it should be understood that it includes the use of hair and fibers of any kind adapted to their uses and purposes, and that my invention is not limited to the number of rows of bristles that may be contained in any brush or broom in which my invention is present.

Having described my invention, what I claim and desire to secure by Letters Patent is:

1. In a brush, the combination of a metal strip, a number of spaced bunches of bristles secured thereto and arranged in a straight row, a separate binding clip sur-

rounding each bunch and secured to said strip said clips having their ends overlapping and having their adjacent edges parallel.

2. In a brush the combination of a metal strip, a number of bunches of bristles therefor, a separate binding clip surrounding each of said bunches, and extending through said strips, the legs of said clips being tapered and overlapped.

3. In a brush the combination of a metal strip, a plurality of bunches of bristles, and a separate binding clip for each of said bunches substantially semi-circular in cross-section, said clips being interlocked with said strips.

4. In a brush the combination of a number of parallel strips having slots there-through arranged in spaced pairs, a number of bunches of bristles, binding clips for each bunch separated from each other, the legs of which clips project through said slots and are flat against said strips, and means for connecting and permanently securing said several strips together in their operative position.

5. In a brush, the combination with a number of spaced parallel strips, means for mounting and locking said strips in their operative position, a plurality of bunches of bristles arranged along said strips, a separate binding clip for each bunch, the ends of said clips passing through said strips and being bent for securing the clips to said strips with their flat sides opposing each other in adjacent rows.

6. In a brush, the combination of a head, strips extending from end to end of said head and each provided with a series of slots, means for connecting said several strips in operative position, a number of bunches of bristles and individual binding clips therefor, the legs of which clips project through said slots and are clinched flat against the surfaces of said strips with the end of one leg extending beyond the end of the other leg.

7. In a brush head the combination of parallel strips provided with slots in spaced pairs, a plurality of bunches of bristles, a sheet metal clip for securing each of said bunches to one of said strips, the legs of which clip taper to points and extend through a pair of said slots, said legs being bent down against the side of said strip with their adjacent edges opposing each other in parallel lines.

In witness whereof, I have hereunto set my hand and affixed my seal, this 17th day of August, A. D. 1916.

VICTOR ADAMS. [L. S.]
